Attorney

UNITED STATES PATENT OFFICE.

CHARLES E. VANHONSEBROUCK, OF SALEM DEPOT, NEW HAMPSHIRE, ASSIGNOR TO DRAPER CORPORATION, OF HOPEDALE, MASSACHUSETTS, A CORPORATION OF MAINE.

STOP MOTION FOR LOOMS.

1,424,956.

Specification of Letters Patent. Patented Aug. 8, 1922.

Application filed April 17, 1922. Serial No. 553,390.

To all whom it may concern:

Be it known that I, CHARLES E. VANHONSEBROUCK, of Salem Depot, in the county of Rockingham and State of New Hampshire, have invented certain new and useful Improvements in Stop Motions for Looms, of which the following is a specification.

The present improvements relate to the means for connecting the shipper handle of a loom to both a warp stop motion and a weft stop motion and are illustrated in the accompanying drawings wherein—

Figure 1 is a side view of so much of the stop mechanism as is necessary for an understanding of the present improvements, a portion of the lay and of the breast beam being shown in vertical section. Fig. 2 is a plan view of the connecting mechanism, portions of the shipper handle and the weft stop mechanism being shown in vertical section. Fig. 3 is a vertical section in the plane indicated by the line 3—3 in Fig. 1.

A, is a portion of the lay; B, is a portion of the breast beam; and C, is a portion of the shipper handle pivoted at a. The shipper handle illustrated is of the type which swings back and forth parallel with the loom side, being such a shipper handle as is shown, for example, in United States Letters Patent of Ambler No. 867,934, October 8, 1907. The illustrated position of the shipper handle is that which it occupies when the loom has been stopped.

The warp stop motion indicated is of the type shown in United States Letters Patent of Ambler No. 885,130, April 21, 1908. This warp stop motion includes a dog D, which, when a warp thread breaks or becomes unduly slack, is automatically lifted into the path of a bunter E, carried by the lay, this bunter being indicated in dotted lines in the accompanying drawings. In Fig. 1, the dog is illustrated in the position which it occupies after the loom has stopped following the breakage of a warp thread. The dog D, is pivotally connected to the upper end of a swinging carrier F, which is pivoted to a fixed stud G. The carrier F swings in a plane parallel to that in which the shipper handle swings.

The weft stop motion indicated is of the type shown in British Letters Patent No. 6, dated January 1, 1909, to the British Northrop Loom Company, wherein a center fork

is employed. Operatively connected to the center fork so as to rise and fall therewith is a dagger H, carried by a rock shaft I, and which cooperates with the upper end of a stop finger J, this part of the stop finger being shown only in dotted lines in the accompanying drawings. This stop finger is pivoted on a stud K, which is adjustable back and forth on a fixed bracket carried by the breast beam. This stop finger is shown in Fig. 1 as occupying the position which it assumes when the loom stops. When the loom is running, the upper end of this stop finger is above the controller L, and in the path of the dagger H, when the weft breaks or becomes exhausted. When the weft is intact the dagger H, is maintained in an uplifted position so as to travel idly above and out of contact with the stop finger J. The stop finger swings in a plane parallel to that in which the shipper handle swings.

The present improvements relate to the mechanism which connects the shipper handle C, to the stop finger J, of the weft stop motion and to the carrier F, of the warp stop motion. The rod 1 has at its forward end a longitudinal slot 2 through which passes a lateral stud 3 on the shipper handle, a pin 4 preventing accidental disengagement of the shipper handle and the rod. An adjusting screw 5 is carried by the front end of the rod with its inner end entering the slot 2, so as to be engaged by the stud 3 when the shipper handle is in its forward position and the loom is running. The screw 5 can be set to such position that the stop finger J, and the carrier F, occupy their functional positions when the loom is running and when the shipper handle is all the way forward. The adjusting screw 5 is maintained in its adjusted position by means of a lock nut 6. At its inner rear end the rod 1 is formed with integral upwardly extending ears 7 and 8 between which is mounted a rock shaft 9. This shaft passes through an eye in the lower end M, of the stop finger J, which extends beneath the pivoted stud K. Consequently, this shaft 9 constitutes a pivotal connection between the stop finger J, and the rod 1. The shaft rocks with respect to both rod and stop finger. The stud 3 passing through the slot 2 supplies the pivotal connection between the rod 1 and the shipper handle C. The rod

is hence pivotally slidingly and adjustably connected to the shipper handle. By reason of these pivotal connections between the rod on the one hand and the shipper handle 5 and the stop finger of the weft stop motion on the other, the rod is always in operative relation to the said shipper handle and finger, although they turn on different centres. Also, by reason of this connection, the 10 rod 1 moves back and forth as the stop finger J, swings on its pivot stud K.

The rod 1 is joined to the carrier F, of the warp stop motion by means of a link 10. This link 10 is pivoted at its rear end 15 11 to the swinging carrier F. As illustrated, this rear end of the link is bent laterally so as to pass through an aperture in the carrier F, and is held in place by a pin 12. The front end of the link 10 passes slidingly 20 through a transverse aperture in the rock shaft 9 and is fastened in correct position by means of a set screw 13 which extends axially into the rock shaft 9. By loosening the set screw 13 the link 10 can slide in the 25 rock shaft so as to bring the carrier F, into correct position relatively to the stop finger, whereupon the set screw 13 is tightened and the proper relative position is maintained.

Since the rock shaft 9 can rock freely 30 within the ears 7 and 8 of the rod 1 and within the eye at the bottom of the stop finger, the link 10 is pivotally connected at both ends. Hence, the finger J and the carrier F, can freely swing on their different 35 centres.

When the carrier F, swings to the left, it pulls upon the link 10, thereby pulling on the rod 1 and hence swinging the shipper handle C, rearwardly to stop the loom.

40 It will be noted that the slot 2 provides for a greater movement of the shipper handle C, as compared with the movement of the carrier F, and the finger J.

When the shipper handle is swung forward 45 to start the loom, its stud 3 encounters the inner end of the screw 5, thereby pulling on the rod 1 and upon the link 10 to restore the stop finger J and the dog D to their normal functional positions ready to 50 act in case the warp thread breaks or becomes unduly slack or the weft thread breaks or runs out.

I claim—

1. A stop motion for a loom including 55 a swinging carrier which is brought into action when a warp thread breaks or becomes unduly slack, a swinging stop finger which is brought into action when a weft thread breaks or runs out, and a shipper handle 60 which swings back and forth in a plane parallel to the planes of swing of said carrier and of said stop finger, said handle having a lateral stud, in combination with mechanism connecting said shipper handle 65 to said stop finger and to said carrier, said

mechanism comprising a rod slotted at its front end to embrace said lateral stud on the shipper handle and a pair of separated ears at its rear end, an adjustable screw at the front end of the rod entering said slot, 70 a rock shaft carried by said ears and extending through an eye in the lower end of said stop finger and constituting a pivotal connection between said rod and stop finger, said rock shaft having a transverse aperture, a link pivotally connected at its rear end to said carrier and slidingly passing through said aperture in said rock shaft, and a set screw passing axially through said rock shaft and acting upon said link to 75 maintain it in definite position relatively to said stop finger.

2. A stop motion for a loom including a swinging carrier which is brought into action when a warp thread breaks or becomes unduly slack, a swinging stop finger which is brought into action when a weft thread breaks or runs out, and a shipper handle which swings back and forth in a plane parallel to the planes of swing of 80 said carrier and of said stop finger, in combination with mechanism connecting said shipper handle to said stop finger and to said carrier, said mechanism comprising a rod pivotally, slidingly and adjustably connected at its front end to the shipper handle, a rock shaft carried by said rod at its rear end and extending through an eye in said stop finger and constituting a pivotal connection between said rod and stop finger, 85 said rock shaft having a transverse aperture, a link pivotally connected at its rear end to said carrier and slidingly passing through said aperture in said rock shaft, and a set screw passing axially through 90 said rock shaft and acting upon said link to maintain it in definite position relatively to said stop finger.

3. A stop motion for a loom including a swinging carrier which is brought into action when a warp thread breaks or becomes unduly slack, a swinging stop finger which is brought into action when a weft thread breaks or runs out, and a shipper handle which swings back and forth in a plane 95 parallel to the planes of swing of said carrier and of said stop finger, in combination with mechanism connecting said shipper handle to said stop finger and carrier, 100 said mechanism comprising a rod pivotally and slidingly connected at its front end to the shipper handle, a rock shaft carried by said rod at its rear end and cooperating with the stop finger to constitute a pivotal connection between said rod and stop finger, 105 and a link pivotally connected at its rear end to said carrier and attached to said rock shaft.

4. A stop motion for a loom including a 110 swinging carrier which is brought into ac-

tion when a warp thread breaks or becomes unduly slack, a swinging stop finger which is brought into action when a weft thread breaks or runs out, and a shipper handle which swings back and forth in a plane parallel to the planes of swing of said carrier and said stop finger, in combination with mechanism connecting said shipper handle to said stop finger and car-

rier, said mechanism comprising a rod attached at its front end to the shipper handle, a rock shaft connecting said connector and stop finger and rocking with respect to both, and a link connected at one end to said carrier and at its other end to said rock shaft. 15

In witness whereof, I have hereunto signed my name.

CHARLES E. VANHONSEBROUCK.
